The ornamental design for a greeting card mask—dog, as shown and described.

DESCRIPTION

FIG. 1 is a perspective view of the greeting card mask—dog of the present invention, in a closed position.

FIG. 2 is a perspective view of the greeting card mask—dog of FIG. 1, in an open position.

FIG. 3 is a front view of the greeting card mask—dog of FIG. 1.

FIG. 4 is a rear view of the greeting card mask—dog of FIG. 1.

FIG. 5 is a right side view of the greeting card mask—dog of FIG. 1, the left side view being a mirror image thereof.

FIG. 6 is a bottom view of the greeting card mask—dog of FIG. 1; and,

FIG. 7 is a top view of the greeting card mask—dog of FIG. 1.

The broken line showing of portions of the greeting card mask—dog is included for the purpose of illustrating environmental structure and forms no part of the claimed design.
